WILLIAM D. BAKER, OF MARSHFIELD, MASSACHUSETTS.

Letters Patent No. 66,282, dated July 2, 1867.

IMPROVED WINDLASS AND CHAIN-STOPPER.

The Schedule referred to in these Letters Patent and making part of the same.

TO ALL WHOM IT MAY CONCERN:

Be it known that I, WILLIAM D. BAKER, of Marshfield, in the county of Plymouth, and State of Massachusetts, have invented a new and improved Chain-Stopper and Windlass for ships and other vessels, and that the following description, taken in connection with the accompanying drawings hereinafter referred to, forms a full and exact specification of the same, wherein I have set forth the nature and principles of my said improvements; by which my invention may be distinguished from all others of a similar class, together with such parts as I claim and desire to have secured to me by Letters Patent.

This invention consists in arranging a plurality of drums and brakes in such a manner that an anchor may be raised with facility and lowered with any degree of speed, the lowering or dropping of the anchor being under the perfect control of the operator. This invention is applicable as a windlass or chain-stopper, or both. In the accompanying sheet of drawings—

Figure 1 is a side sectional view of my invention, taken in the line *x x*, fig. 2.

Figure 2, a plan or top view of the same.

Similar letters of reference indicate corresponding parts.

A A A represent three parallel shafts, which are placed in a suitable frame, B, and have each a drum, C, on them, around all of which the anchor-chain D passes, said chain making one convolution around each drum, as shown clearly in fig. 2. These drums are on one end of the shafts A, and on the opposite ends pulleys E are placed and firmly keyed or secured. These pulleys E have each a metallic strap, F, passing over them, and all of these straps are secured at one end to a shaft, G, which is provided with a hole, *a*, to receive a hand-lever. The opposite ends of these metallic straps are secured to pins *b*, which are driven in the frame B near their respective pulleys E, each strap passing around its pulley so as to be in contact with the greater portion of its periphery, as shown clearly in fig. 1.

It will be seen from the above description that by turning the shaft G, through the medium of the hand-lever which is fitted in it, all the straps F will be made to bind or bear upon the peripheries of all the pulleys, as all of the straps are attached at one end to the shaft G. Hence the speed of the descent of the anchor may be regulated as desired, owing to the great amount of friction which may be brought to bear upon the peripheries of the pulleys E; it being sufficient, if necessary, to hold the anchor in a suspended state. By having the shafts A connected by gears so that all may be turned by the application of power to any one of them, the device may be used as a windlass. When used as a chain-stopper only, the anchor-chain D passes from the windlass around the drums C, as shown, the device being placed on the vessel between the windlass and the hawse-holes.

Having thus described my invention, I claim as new, and desire to secure by Letters Patent—

A ship's windlass or chain-stopper, or both, composed of plurality of shafts A, provided with drums C and pulleys E, with metallic straps F applied to them, and all connected at one end to a single shaft, G, substantially as shown and described.

The above specification of my invention signed by me this 28th day of March, 1867.

WILLIAM D. BAKER.
